(57) **CLAIM**

The ornamental design for a handheld gardening tool, as shown and described.

DESCRIPTION

FIG. 1 is a front, top, right side perspective view of a handheld gardening tool showing my new design;

FIG. 2 is a front, top, left side perspective view thereof;

FIG. 3 is a front, bottom, left side perspective view thereof;

FIG. 4 is a front, bottom, right side perspective view thereof;

FIG. 5 is a front view thereof;

FIG. 6 is a left side view thereof;

FIG. 7 is a right side view thereof;

FIG. 8 is a top view thereof; and,

FIG. 9 is a bottom view thereof.

The broken line showing of a handheld gardening tool is for the purpose of illustrating portions of the article and forms no part of the claimed design.

1 Claim, 8 Drawing Sheets
